UNITED STATES PATENT OFFICE.

JOHN LUKASZEWSKI, OF CHICAGO, ILLINOIS.

AUTOMATIC STARTER FOR PHONOGRAHS.

Application filed February 24, 1923. Serial No. 620,954.

To all whom it may concern:

Be it known that I, JOHN LUKASZEWSKI, a citizen of the United States of America, residing at Chicago, in the county of Cook 5 and State of Illinois, have invented certain new and useful Improvements in Automatic Starters for Phonographs, of which the following is a specification.

This invention relates to certain new and 10 useful improvements in automatic starters for phonographs and includes a clock having an alarm mechanism associated with the brake lever or foot of the phonograph turn table for shifting the brake lever at the desired time to release the turn table and permit the playing of a record, the device being intended for use in lieu of the ordinary alarm of a clock mechanism.

With the above and other objects in view 15 as the nature of the invention is better understood, the same consists of the novel form, combination and arrangement of parts hereinafter more fully described, shown in the accompanying drawing and 20 claimed.

In the drawing, wherein like reference characters designate corresponding parts throughout the several views,

Figure 1 is a fragmentary front elevational view of a phonograph constructed in 30 accordance with the present invention, the tone chamber of the phonograph being provided with a hinged door that carries a clock mechanism,

Figure 2 is a top plan view of the phonograph with the cover removed showing the 35 brake arm in engagement with the turn table, the latter supporting a disk record with the tone arm and sound box resting thereon,

Figure 3 is a vertical sectional view of the 40 upper end of the phonograph showing the clock supported on the hinged door of the tone chamber, the brake rod for the turn table, and the connections between the brake rod and winding key of the alarm mechanism for the clock.

Figure 4 is a detail horizontal sectional view with the brake rod illustrated by dotted lines in its shifted released position,

Figure 5 is a fragmentary detail view 50 showing the block to which the lower inner end of the brake rod is attached with the block illustrated in its shifted position by dotted lines,

Figure 6 is a detail sectional view taken 55 on line VI—VI of Fig. 5 showing the head

of the winding key for the alarm mechanism seated in the block to which the brake arm is attached, and

Figure 7 is a detail sectional view taken 60 on line VII—VII of Fig. 6.

Referring more in detail to the accompanying drawings, there is illustrated a phonograph including a box or casing 1 having a tone chamber 2 adjacent the upper end 65 thereof, the front end of the tone chamber being provided with a horizontally swinging hinged door 3. The tone chamber is provided with the usual upper wall 4 above which a turn table 5 is rotatably supported, 70 and with which turn table, a tone arm 6 is associated as shown in Fig. 2.

The mechanism for effecting the automatic starting of the turn table 5 includes a clock casing 7 having the front face there- 75 of set in a cutaway portion 8 in the door 3 of the tone chamber, the clock casing 7 being carried by the bracket 9 that is attached to the rear face of the door 3 adjacent the upper end thereof as clearly shown in Figs. 80 1 and 3. The clock casing contains the usual mechanism, the main spring thereof being wound by the key 10, the alarm mechanism being set by the key 11 and wound by the key that includes the shank 12 and 85 head 13 of the form best illustrated in Figs. 6 and 7.

A standard or bracket 14 is supported upon the floor board 15 of the tone chamber 2, and rotatably supports at the upper end 90 thereof a laterally positioned vertical plate 16, to the outer face of which a block 17 is secured as shown in Fig. 6. The outer face of the block 17 is provided with a socket 18 of a configuration corresponding to the head 95 13 of the alarm mechanism key, the head of the key being received in said socket when the door 3 of the tone chamber is closed.

The brake rod 19 for the turn table 5 is 100 of angle formation as shown most clearly in Fig. 3, the inner lower end of the brake rod 19 being anchored as at 20 to the upper edge of the block 17, while the upper end of said brake rod extends through an opening 21 105 in the upper wall 4 of the tone chamber and is provided upon the free end thereof with an arcuate brake shoe 22. The upper end of the brake rod that is disposed adjacent the upper wall 4 of the tone chamber is provided with an elongated slot 23 that receives the pin 24 depending from the upper wall 110

4 for guiding the shifting movements of the brake rod. The brake shoe 22 of the rod 19 is normally maintained in engagement with the peripheral edge of the turn table 5 by the spring 25 shown in Fig. 4.

In the operation of the device, the door 3 of the tone chamber 2 is moved to an outward position permitting access to the winding keys for the main spring and alarm mechanism of the clock case 7, the latter being bodily movable with the door 3, and the alarm being set by the key 11 in the usual manner. When the door is moved to a closed position, the head 13 of the alarm key is vertically positioned as shown in Figs. 6 and 7 and is received in the socket 18 formed in the outer face of the block 17, the brake shoe 22 being normally maintained in frictional contact with the peripheral edge 20 of the turn table 5 by the spring 25 as shown in Figs. 3 and 4. In lieu of the sounding of the usual alarm mechanism of the clock case, the key head 18 is rotated at the time that the alarm is set, causing a partial rotation of the block 17 and plate 16, the block 17 being interlocked with the key head 13 effecting a sliding movement of the brake rod 19 as shown by dotted lines in Fig. 4 to displace the brake shoe 22 from engagement 25 with the peripheral edge of the turn table 5 and permit rotation thereof with a record mounted thereon as shown in Fig. 2, rotary movement of the alarm key being limited by the chain 26 attached at one end of the shank 12 of the alarm key and having the other end thereof attached to the eye bolt 27 carried by the rear face of the lock casing 7. The playing of the record may be readily discontinued by moving the door 3 to an open position to disengage the alarm key 30 from the block 17 and permit the spring 25 to shift the brake shoe 22 into engagement with the turn table.

While there is herein shown and described the preferred embodiment of the present invention, it is nevertheless to be understood that minor changes may be made therein without departing from the spirit and scope of the invention as claimed.

50 What is claimed as new is:—

1. In a phonograph attachment of the type described, a turn table having a brake rod associated therewith, a hinged door carried by the phonograph, a clock case including alarm mechanism carried by the door, a rotatable block connected to the in-

ner end of the brake rod, and a winding key for the alarm mechanism adapted to interlock with the block for shifting the block and brake rod when the alarm mechanism is 60 released.

2. In a phonograph attachment of the type described, a phonograph casing, a sound box formed therein, a hinged door for closing the front end of said sound box, a turn table rotatably mounted above the top wall of said sound box, a clock casing including alarm mechanism carried by said door, a brake rod carried by the bottom wall of said sound box and extending through an opening formed in the top wall of said sound box to position its outer end in proximity to the periphery of the turn table, and means connecting the inner end of the brake rod with the clock alarm mechanism 70 for releasing the turn table when the alarm mechanism is released.

3. In a phonograph attachment of the type described, a phonograph including a sound box, a turn table rotatably positioned thereabove, and a hinged door for closing one wall thereof, a clock casing including alarm mechanism carried by said door, a winding key for the alarm mechanism, a brake rod supported by the bottom wall of said sound box and projecting through an opening formed in the top wall for frictionally engaging the periphery of the turn table, means for connecting the inner end of the brake rod with said winding key when the said door is in its closed position, and a section of chain connected to the winding key and clock casing for limiting rotary movement of said key.

4. In a phonograph attachment of the type described, a phonograph including a sound box, a turn table rotatably mounted thereabove, and a hinged door for forming one end wall thereof, a clock casing including alarm mechanism carried by said door, a winding key for said alarm mechanism, a standard carried by the bottom wall of said sound box, a block rotatably supported by the upper end of said standard adapted for engaging said winding key when the door is in its closed position, and a brake rod carried by said block extending through an opening formed in the top wall of said sound box for frictionally engaging the peripheral edge of said turn table.

In testimony whereof I affix my signature.
JOHN LUKASZEWSKI.
